UNITED STATES PATENT OFFICE

2,179,363

CONTROL MEANS FOR TRANSMITTERS

Donald E. Watts, Schenectady, N. Y., assignor to
General Electric Company, a corporation of
New York

Application June 19, 1937, Serial No. 149,117

6 Claims. (Cl. 250—17)

My invention relates to radio transmitter apparatus, and particularly to starting and control arrangements for keyed transmitters, wherein starting of the transmitter circuits and keying of the transmitter may be accomplished either at the transmitter or from a remote point.

The general object of the invention is to provide improved and simplified local and remote starting, control, and keying means for transmitter apparatus supplied from an alternating current source and having a keying circuit supplied from a direct current source.

A further object is to provide an improved indicating means, operating in conjunction with the local and remote control means, to indicate power conditions in the circuits supplied with alternating current power.

A still further object is to provide an improved means for standby operation of the transmitter apparatus whereby tube elements of the apparatus are maintained in readiness for immediate operation of the system either from the local or the remote control point.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing, in which the single figure illustrates diagrammatically a radio transmitter apparatus in which my invention has been embodied.

In the drawing, the numeral 1 designates generally a local control station at the transmitter apparatus, and the numeral 2 designates a remote control station. An alternating current source represented by the power lines 3 is adapted to be connected through a main switch 4 and a relay 5, having an actuating winding 6 and extra contacts 7, to the primary of an anode transformer 8 of a rectifier 9 for supplying anode current to the various tubes (not shown) of the transmitter. Two lines of the source 3 are connected to the primary of a transformer 10 for supplying current, through a switch and relay means to be presently described to the primary of a transmitter-cathode transformer 11, to the primaries of the cathode transformer 12 and the anode transformer 13 of a keying-circuit supply rectifier 14, and to the primary of the cathode transformer 15 of the rectifier 9.

For controlling the current from transformer 10 to the foregoing elements, one terminal, 16, of

transformer 10 is connected to two terminals 17 and 18 of a local start-stop double-pole switch 19, through the actuating winding 20 of a starting contactor or relay 21 and through a power indicator or signal lamp 22. The opposite terminals 23 and 24 of the switch 19 are connected respectively to terminals 25 and 26 of a local-and-remote control triple-pole switch 27. That one of the blades 28 of the latter switch which is adapted to be connected to terminal 23 of switch 19 is connected through contacts 29 of an interlock relay 30 to the other terminal 31 of transformer 10.

Terminal 16 of transformer 10 is further connected through a regulating resistance 32 to one terminal of the primary of transmitter-cathode transformer 11, the other terminal of the latter primary being adapted to be connected through contacts 33 of relay 21, contacts 34 of relay 30, and contacts 35 of relay 21 to the other terminal 31 of transformer 10. Terminal 16 of transformer 10 is connected also to a terminal of the actuating winding 36 of a time-delay relay 37 and to terminals of the primaries of cathode transformers 12 and 15. The opposite terminals of the latter actuating winding and primaries are adapted to be connected through contacts 34 of relay 30 and contacts 35 of relay 21 to terminal 31 of transformer 10.

Terminal 16 of transformer 10 is adapted to be connected also through the contacts 33 of time-delay relay 37 and contacts 33 of relay 21 to a terminal of the primary of anode transformer 13 and to a terminal of the actuating coil 6 of relay 5. The opposite terminal of the latter primary is adapted to be connected through contacts 40 of relay 21, contacts 34 of relay 30, and contacts 35 of relay 21 to terminal 31 of transformer 10, and the opposite terminal of actuating winding 6 is adapted to be connected to terminal 31 of transformer 10 through contacts 33 of relay 21, contacts 34 of relay 30 and contacts 35 of relay 21.

Terminal 16 of transformer 10 is adapted to be connected also through extra contacts 7 of relay 5 to one terminal of an anode current indicator or signal lamp 41 at the local control station 1, the opposite terminal of which lamp is adapted to be connected to terminal 31 of transformer 10 either through start-stop switch 19, contact 25 and blade 28 of local-remote control switch 27 when this switch is in its local control position as illustrated, and contacts 29 of relay 30, or through contact 26 and blade 42 of local-remote control switch 27 when this switch is in its lower or re-

remote-control position, a start-stop switch 43 at remote control station 2, contact 44 and blade 28 of switch 27, and contacts 28 of relay 30. Terminal 16 of transformer 10 is adapted to be connected also through extra contacts 7 of relay 5 to one terminal of an anode current indicator or signal lamp 45 at the remote-control station 2. The opposite terminal of indicator 45 is adapted to be connected to terminal 31 of transformer 10 through remote start-stop switch 43, contact 44 and blade 28 of local-remote control switch 27 when this switch is in its lower or remote-control position, and contacts 29 of relay 30.

A keying circuit (not shown) for the transmitter apparatus is adapted to be connected in circuit with the terminals 46 and 47 of the keying-circuit supply rectifier 14 by a keying means represented by a key 48 at the local control station 1 when local and remote control switch 27 is either in its local or its remote control position, and by a key 49, at the remote control station 2, only when the switch 27 is in its lower or remote control position. The terminals of local control key 48 are connected respectively to blades 28 and 50 of local-and-remote control switch 27 and the terminals of remote control key 49 are connected respectively to terminals 46 and 51 of switch 27. The same wire or lead 52 thus functions as a connection means between the lower terminal 44 of switch 27 at the local station 1 and the start-stop switch 43 and key 49 at the remote control station 2, a total of four wires only being required to connect the start-stop means, the keying means and the anode current indicator at remote control station 2 of the local control station 1.

To enable the cathodes of the system to be energized without energization of the anode circuits and anode current indicators until desired, a stand-by switch 53 is connected across the contacts 35 of starting contactor or relay 21.

To energize the interlock relay 30 continuously during operation of the system, the terminals of its actuating winding 54 are connected respectively to the terminals 16 and 31 of transformer 10. Emergency stop means, represented by an emergency stop switch 55, are included in one or both of the leads, as lead 56, connecting actuating coil 54, of interlock relay 30 to transformer 10.

In operation, assuming it is desired to control the system from local station 1, main switch 4 being closed and stand-by switch 53 open and the actuating winding 54 of interlock relay 30 being energized by current from transformer 10 to close contacts 29 and 34, the local-and-remote control switch 27 is placed in its upper, or local control, position and local start-stop switch 43 is closed. Power indicator lamp 22, and actuating coil 20 of starting contactor 21, are thereupon energized by current from transformer 10 through the circuit extending from terminal 16 of transformer 10, through coil 20 and lamp 22 in parallel, lower contacts of switch 19, contact 25 and blade 28 of switch 27, contacts 28 of relay 30, back to terminal 31 of transformer 10. Upon energizing of actuating coil 54 as above described, contacts 35, 39, 49 and 23 of relay 21 are closed. The following elements are then also energized from transformer 10: transmitter-cathode transformer 11 is energized through the circuit extending from terminal 16 of transformer 10, through resistance 32, the primary of transformer 11, contacts 33 of contactor 21, contacts 34 of relay 30, contacts 25 of contactor 21, back to terminal 31 of

transformer 10; keying-circuit-rectifier cathode transformer 12 is energized through the circuit extending from terminal 16 of transformer 10, through the primary of transformer 12, contacts 36 of relay 30, contacts 25 of contactor 21, back to terminal 31 of transformer 10; transmitter-anode-rectifier cathode transformer 15 is energized through the circuit extending from terminal 16 of transformer 10, through the primary of transformer 15, contacts 34 of relay 30, contacts 35 of contactor 21, back to terminal 31 of transformer 10; and actuating coil 36 of time-delay relay 37 is energized through the circuit extending from terminal 16 of transformer 10 through coil 36, contacts 34 of relay 30, contacts 35 of contactor 21, back to terminal 31 of transformer 10. After a predetermined interval, for example thirty seconds, the contacts 38 of time-delay relay 37 close, thereby causing keying-circuit rectifier-anode transformer 13 to be energized through the circuit extending from terminal 16 of transformer 10, through contacts 38 of relay 37, contacts 39 of contactor 21, the primary of transformer 13, contacts 40 of contactor 21, contacts 34 of relay 30, contacts 35 of contactor 21, back to terminal 31 of transformer 10, and also causing actuating coil 6 of relay 5 to be energized from transformer 10 through the circuit extending from terminal 16 of transformer 10, through contacts 38 of relay 37, contacts 39 of contactor 21, contacts 34 of relay 37, contacts 35 of contactor 21, and back to terminal 31 of transformer 10. The contacts of relay 5 thereupon close causing transmitter-anode transformer 8 to be energized from lines 3 directly, and anode current indicator 41 to be energized from transformer 10 through the circuit extending from terminal 16 of transformer 10, contacts 7 of switch 5, indicator 41, switch 19, contact 25 and blade 28 of switch 27, contacts 29 of relay 30, back to terminal 31 of transformer 10.

The transmitter keying circuit is now ready to be energized from keying-circuit rectifier 14 and the transmitter may be keyed by key 48 at the local station 1. At the same time connection of the remote control station 2 to the starting, indicating, and keying circuits of the system is cut off at the local-and-remote control switch 27.

Assuming now that it is desired to start and to key the system from remote station 2, main switch 4 and local start-stop switch 43 being in closed position as before, the local-and-remote control switch 27 is placed in its lower or remote control position and remote start-stop switch 43 is closed. Actuating winding 20 of starting contactor 21 is thereupon energized from transformer 10 through the circuit extending from terminal 16 of transformer 10 through winding 20, the upper contacts 18 and 24 of switch 19, contact 26 and blade 42 of switch 27, remote control switch 60 43, contact 44 and blade 28 of switch 27, contacts 29 of interlock relay 30, back to terminal 31 of transformer 10. Transformers 11, 12 and 15 actuating coil 36 of time-delay 37 are thereupon energized, followed by the closing of the time-delay relay contacts 38 and the consequent energizing of transformer 13, actuating coil 6 of relay 5, transformer 8, and anode current indicator 41, as above explained in connection with operation from the local station. Remote anode-current indicator or lamp 45 is also energized, by current from transformer 10 through the circuit extending from terminal 16 of transformer 10 through contacts 7 of relay 5, lamp 45, switch 43, contact 44 and blade 28 of switch 27, contacts 29 of relay 75

36, back to terminal 31 of transformer 10. The system may now be keyed either from the local station 1 by key 48 or from the remote station 2 by key 49. In the latter case the keying current 5 from rectifier 14 flows from the rectifier, through the keying circuit of the transmitter, blade 50 and contact 51 of switch 27, to the remote station key 49, thence through line 52, contact 44 and blade 28 of switch 27, and back to the rectifier.

10 To place the system in stand-by condition, wherein only the cathodes of the rectifiers 9 and 14, and the actuating coil 54 of interlock relay 30, are maintained in energized condition, main switch 4 being closed and interlock relay 30 15 being held in closed position by current from transformer 10, local start-stop switch 19 is assumed to be open if local-and-remote control switch 27 is in its upper or local control position and remote start-stop switch 43 is assumed to be 20 open if switch 27 is in its lower or remote control position. Standby switch 53 is closed thereby causing transformer 10 to energize cathode transformers 12 and 15 of rectifiers 14 and 9 respectively, through a circuit extending from the 25 terminal 16 of transformer 10, through the primary windings of transformers 12 and 15 in parallel, contacts 34 of relay 30, switch 53, and back to terminal 31 of transformer 10.

Closing of standby switch 53 also causes transformer 10 to energize actuating winding 36 of time-delay relay 37 through the circuit extending from terminal 16 of transformer 10, through winding 36, contacts 34 of relay 30, switch 53, back to terminal 31 of transformer 10, the contacts 38 of relay 37 closing after the predetermined time interval. Anode current is not, however, supplied to transformers 13 and 8, since contacts 39 of relay 21, connected to transformer 13 and to the actuating winding of relay 5, are 40 main open. If now the transmitter is started by means either of the local switch 19 or of the remote switch 43, switch 27 being in the appropriate position for local or for remote operation, anode voltage is immediately applied to the keying-current rectifier 14 through transformer 13 which is energized from transformer 10 through the circuit extending from terminal 16 of transformer 10, through contacts 38 of time-delay relay 37, contacts 39 of contactor 31, the primary of 45 transformer 13, contacts 40 of contactor 21, contacts 34 of relay 30, contacts 35 of contactor 21, back to terminal 31 of transformer 10. At the same time actuating winding 6 of switch 5 is energized from transformer 10 through the circuit 50 extending from terminal 16 of transformer 10, through contacts 38 of relay 37, contacts 39 of contactor 21, winding 6, contacts 33 of contactor 21, contacts 34 of relay 30, contacts 35 of contactor 21, back to terminal 31 of transformer 10. 55 Switch 5 thereupon closes and anode voltage is supplied to rectifier 9 through transformer 8, rectifier 9 then applying anode voltage to the transmitter anodes. Further, the transmitter cathodes also are energized from transformer 11, which is energized from transformer 10 through the circuit extending from terminal 16 of transformer 10, through resistance 32, the primary of transformer 11, contacts 33 of contactor 21, contacts 34 of relay 30, contacts 35 of contactor 21, back to terminal 31 of transformer 10. The system is then ready for keying as hereinabove described.

If it is found desirable, from the standpoint of tube operation to energize the transmitter cathodes continuously when the controls are in the

standby position, it is possible to accomplish this by connecting a link across contacts 33 of relay 21.

In case the emergency stop means represented by stop switch 55 is operated, actuating coil 54 of interlock relay 30 is de-energized. By the opening of contacts 34 of relay 30, all of the cathode transformers 11, 12 and 15 are disconnected from supply transformer 10. By the opening of the other contacts 29 of relay 30 the actuating winding 20 of starting relay 21 is also de-energized, thus insuring the opening of the contacts of the latter relay, and complete stoppage of the system, when the interlock relay 30 is de-energized.

My invention has been described herein in a particular embodiment for purposes of illustration. It is to be understood, however, that the invention is susceptible of various changes and modifications and that by the appended claims I intend to cause any such modifications as fall within the true spirit and scope of my invention.

What I claim as new and desire to secure by Letters Patent of the United States, is:

1. In a transmitter apparatus comprising a cathode heating circuit, an anode supply circuit, and a keying circuit, means to control said apparatus from a local station at said apparatus and subsequently from a remote station, said means including a local and remote switch at said local station, means operative when said switch is in its local position to energize said cathode circuit, to energize said anode circuit after a predetermined time interval, to operate said keying circuit from said local station only, and to prevent control of said circuits from said remote station, and means operative when said switch is in its remote position to energize said cathode and anode circuits and to operate said keying circuit from said remote station.

2. In a transmitter apparatus comprising a local and a remote control station, a cathode heating circuit and an indicator therefor at said local station, an anode supply circuit and indicators therefor at both said stations, and a keying circuit, a local and remote control switch at said local station, means operative when said switch is in local position to energize said cathode heating circuit and said indicator therefor, to energize said anode circuit and the local station indicator therefor after a predetermined time interval, to operate said keying circuit from said local station only, and to prevent control of said circuits and said anode circuit indicators from said remote station, and means operative when said switch is in its remote position to operate said keying circuit and to energize said cathode circuit, said anode circuit, and the remote station indicator therefor from said remote station.

3. In combination, in a transmitter apparatus, a current source, a cathode heating circuit, an anode supply circuit, a time-delay relay adapted to connect said source to said anode circuit, a keying circuit, a local and remote control switch, a normally open standby switch, means operative upon closing of said standby switch to disconnect said cathode heating circuit and said anode supply circuit from said source, means operative when said first-named switch is moved to its local position while said standby switch remains closed to connect said anode circuit to said source through said relay, to operate said keying circuit only from a point at said apparatus, and to prevent control of said apparatus from a remote

point, and means operative when said first-named switch is moved to its remote position while said standby switch remains closed to connect said anode circuit to said source through said relay 5 and to operate said keying circuit from said remote point.

4. In a transmitter apparatus comprising a cathode heating circuit, an anode supply circuit, and a keying circuit, means to control said apparatus from a local station at said apparatus and subsequently from a remote station, said means including a local and remote switch at said local station, means operative when said switch is in its local position to energize said cathode and anode 10 circuits, to operate said keying circuit from said local station only, and to prevent control of said circuits from said remote station, means including at said remote station a start-stop switch only to energize said cathode and anode circuits through 15 said local and remote switch when said last-named switch is in its remote position, and means including at said remote station keying contacts only to operate said keying circuit through said local and remote switch when said last-named 20 switch is in its remote position.

5. In a transmitter apparatus comprising a local and a remote control station, a cathode heating circuit and an indicator therefor at said local station, an anode supply circuit and indicators therefor at both stations, and a keying circuit, a local and remote control switch at said local station, means operative when said switch is in its local position to energize said cathode 25 circuit and said indicator therefor, to energize 30 said anode circuit and the local station indicator 35

therefor, to operate said keying circuit from said local station only, and to prevent control of said circuits and said anode circuit indicators from said remote station, means including at said remote station a start-stop switch only to energize 5 through said local and remote switch said cathode and anode circuits and said remote station indicator for said anode circuit when said last-named switch is in its remote position, and means including at said remote station keying contacts 10 only to operate said keying circuit through said local and remote switch when said last-named switch is in its remote position.

6. In combination, in a transmitter apparatus, a current source, a cathode heating circuit, an anode supply circuit, a time delay relay adapted 15 to connect said source to said anode circuit, a keying circuit, a local and remote control switch, a standby switch, means operative when said first-named switch is moved to its local position while said standby switch remains closed to connect said anode circuit to said source through said relay, to operate said keying circuit from a point at said apparatus only, and to prevent control of said apparatus from a remote point, means including at said remote point a start-stop switch only to connect said anode circuit to said source through said relay and said local and remote switch when said last-named switch is moved to its remote position, and means including at said 20 remote point keying contacts only to operate said keying circuit through said local and remote switch when said last-named switch is moved to its remote position.

DONALD E. WATTS.
